COMBINATION MOORING BIT, CLEAT, CHOCK,
LIGHT AND LIFT

Edward B. Cahen, 14521 NW. 13th Road,
Miami, Fla. 33167

Filed Oct. 27, 1969, Ser. No. 19,740

Term of patent 14 years

Int. Cl. D12—14

U.S. Cl. D8—232

FIG. 1

FIG. 3

FIG. 4

FIG. 5

FIG. 6

FIG. 1 is a perspective view of a combination mooring bit, cleat, chock, light and lift showing my new design.

FIG. 2 is a side elevational view.

FIG. 3 is a top plan view.

FIGS. 4 and 5 are front and rear elevational views, respectively.

FIG. 6 is a bottom plan view thereof.

I claim:

The ornamental design for a combination mooring bit, cleat, chock, light and lift, substantially as shown.
